Attn:

United States Patent Office.

NELSON O. TIFFANY, OF BUFFALO, NEW YORK.

Design No. 4,489, dated November 22, 1870.

DESIGN FOR A SCHOOL-SEAT HINGE.

The Schedule referred to in these Letters Patent and making part of the same.

I, NELSON O. TIFFANY, of Buffalo, in the county of Erie and State of New York, have invented and produced a new and original Design for a Seat-Hinge for School-Desks, of which the following is a specification.

My invention relates to the external shape or configuration of the two members of the hinge and their patterns.

The nature of the design is fully represented by the accompanying drawings, in which—

Figures 1 and 2 are perspective views of the complete hinge, taken from different points, showing opposite sides of the same, with the seat-arm in different positions.

A represents the seat-arm, and

B, the member formed on or attached to the desk.

C is an arm for attaching the member B to a wood end, being designed especially for the bent wood end patented by Wesley Chase, March 8, 1870.

Claims.

I claim as my invention—

1. The form or configuration of the members A B of a seat-hinge for school-desks, substantially as shown and described.
2. The form or configuration of the attaching-arm C, as represented.

NELSON O. TIFFANY.
